UNITED STATES PATENT OFFICE

2,085,622

SCREW PUMP

Rudolph Witt, Northfield, Ohio

Application July 24, 1933, Serial No. 682,013

1. Claim. (Cl. 103—89)

The invention relates to a laundry apparatus and more especially to a pump for a laundering machine.

The primary object of the invention is the provision of a pump of this character, wherein fluid will be controlled for the successful working of the laundry apparatus and enables a continuous operation without requiring close attention on the part of an operator.

10 Another object of the invention is the provision of a pump of this character, wherein all the water used in the laundering apparatus will be forcibly discharged and delivered at any convenient or preferred point.

15 A further object of the invention is the provision of a pump of this character, wherein the construction and arrangement of parts will be such that efficiency is assured and the life thereof prolonged.

20 With these and other objects in view, the invention consists in the features of construction, combination and arrangement of parts as will be hereinafter more fully described, illustrated in the accompanying drawing, which discloses the preferred embodiment of the invention and pointed out in the claim hereunto appended.

In the accompanying drawing:

Figure 1 is a vertical sectional view through a washing machine showing the pump constructed in accordance with the invention in association therewith.

Figure 2 is a longitudinal section of a controlling valve associated with the pump.

Figure 3 is a detail plan view of a reversing valve shown in Figure 1.

Similar reference characters indicate corresponding parts throughout the several views in the drawing.

Referring to the drawing in detail and more especially now to Figure 1, there is shown conventionally an electric motor 1 of any approved type and suitably supported. The motor is so disposed that its shaft 2 extends vertically and projects through the upper end of the motor casing, and to the upper end of said motor casing is secured an intermediate casing 3 having a vertically disposed bore 4 which constitutes a pressure chamber, a sleeve 5 having an external helical rib or screw 6 being disposed within said bore and fitted on and threaded to the upper end of the shaft 2 of the motor. In assembling the parts a ball 7 is preferably disposed within the sleeve at the closed end of the same to receive the thrust from the end of the shaft 2 and maintain the parts in an efficient working relation.

The rib or screw 6 should be of such external diameter that it will fit closely within the bore 4 and consequently, when rotated, will impart movement and pressure to a fluid delivered to said chamber.

The intermediate casing 3 is so constructed as to provide a fluid way 8 for the exhaust and return of a driving fluid, this way being shown in Figure 1 of the drawing as being connected with pipes 9 and 10, respectively, which lead to and from a rotor for driving a wringer (not shown). Other fluid conducting pipes may be connected with this way and a suitable reservoir may be provided to contain sufficient fluid to insure proper operation at all times, it being understood that it is intended to employ some non-compressible fluid, such as oil, as a driving medium and this fluid will be put under pressure and circulated through the proper pipes and actuating elements by the action of the pressure screw or rib 6.

In the upper end of the bore 4 there is mounted a controlling valve 11 which is preferably of the turning plug type, but which may, of course, be of any suitable approved construction whereby various speeds may be obtained for selective speed control in washing.

In the illustrated arrangement the plug 12 of the valve is tapered and extends transversely or across the bore 4, as shown more clearly in Figure 2, the plug 12 being constructed with a longitudinal bore 13 opening through one end only thereof and communicating with radially disposed diametrically opposite ports 14, whereby the flow of liquid may be permitted from the bore 4 or may be cut off and, when permitted, will be directed into the rotor presently described.

A stem 15 extends from the closed end of the plug 12 and is fitted at its outer extremity with a handle 16 of any approved form, the same being extended through a packing 17 to prevent leakage. The open end of the bore 13 aligns with a suitable nipple 18 having coupled therewith the pipe 9.

The upper end of the intermediate casing 3 is provided with an outstanding flange 20 mating with a corresponding flange 21 on a tub-supporting frame 22 and fastening bolts 23 are inserted through these mating flanges to secure the frame to the intermediate casing 3. The confronting ends or sides of the frame and the casing are suitably formed to define a circular chamber into which the fluid is delivered from the bore 4.

The intermediate casing 3 is constructed, as shown in Figure 2 of the drawing, with a passage 24 aligned with the ports 14 of the con-

trolling valve and has the branch leads 25. The circular chamber 26 into which the driving pressure fluid is delivered contains a stationary abutment or gate 27 which extends between the wall 5 of the chamber and the hub 28 of a piston or oscillating wing 29 which has its free end in close sliding relation to the wall and is keyed or otherwise secured to an agitator shaft 30 which extends upwardly through the frame of the machine and into the tub of the machine, as shown in Figure 1 of the drawing. The abutment 27 is secured rigidly in place by a bolt 31 inserted downwardly through the cover 32 into the top of the abutment, as is shown in Figure 1, or 10 any other desired method of fastening may be used. Dowel pins 33 may be provided so as to aid in properly placing the abutment when assembling the parts. The lower edge of the abutment is constructed with a groove or recess 34 15 extending through the sides thereof and in the roof of this recess is a groove 35. In the particular embodiment of the invention which is illustrated, a sliding valve 36 is engaged through the recess 34 and groove 35, the valve consisting of an arcuate plate having a central guide rib 39 on its upper side which fits in and passes through the groove 35 to guide the valve in its movements. The sides of the valve engage the end walls of the recess 34 to aid in guiding the 20 valve, as will be understood. The valve is provided with openings or ports extending vertically therethrough, one port 40 being located adjacent each inner corner of the valve and other ports 41 being located at the outer side of the rib 39 adjacent the ends thereof and at opposite sides of a radial line passing centrally through the valve. The ports 40 constitute inlet ports and are adapted to alternately register with the leads 25, while the ports 41 constitute outlet 25 ports and are adapted to alternately register with ports leading to the fluid way 8. It will be understood that fluid is admitted to the chamber 26 through an inlet port at one side of the abutment 27 and will act upon the piston to drive it through the chamber to the opposite side of the abutment, whereupon the valve will be shifted so that the fluid which has just actuated the piston will be permitted to exhaust and a fresh supply of driving fluid will be admitted to return the piston to its first position, this operation being continuous as long as the prime motor 1 is driven so that the piston will be oscillated and an oscillatory movement imparted to the agitator shaft 30. The valve is provided 35 with recesses 44 in its upper side adapted to be engaged by detents 45 mounted in the abutment and bearing constantly on the valve, the detents springing automatically into engagement with one of the recesses 44, as this particular recess 40 is brought into position below its companion detent, whereby the movement of the valve will be arrested and it will be held in its set position until again shifted by the fluid force.

In the arrangement shown in Figure 3, fluid 45 is being admitted into the chamber 26 through the inlet port 40 above the abutment and the port 41 below the abutment is serving as an exhaust port, the piston being driven in the direction indicated by the arrow.

70 The piston 29 is secured to the agitator shaft 30, as has been stated, in any approved manner

and said shaft depends below the piston to journal in a bearing 46 formed in the intermediate casing 3, a bushing 47 being interposed in the bearing to take up wear and maintain the proper alignment of the shaft. A similar bushing 48 is 5 provided in a bearing 49 in the frame 22 above the actuator or working chamber 26, as is clearly shown in Figure 1. A cap plate 50 is secured upon the frame above the bushing 48 and this chamber is intended to be filled with lubricant. 10 A seal is provided consisting of a bellows 52 secured at its upper end below the cap plate 50 and having at its lower end a washer or sealing ring 53 which bears upon the shoulder of the shaft 30, an expansion spring 54 being interposed between the plate 50 and said sealing ring so as to hold the ring in proper contact with the shoulder of the shaft. A bellows seal is provided at the lower end of the pressure screw, as shown at 55, the screw being provided with an 15 annular rib 56 upon which the bellows seal rests and a non-circular surface 57 being provided below said rib 56 so that a turning tool may be engaged with the screw to facilitate the 20 securing of the same in position upon the motor shaft 2.

A portion of a tub is indicated at 58 and the same is preferably constructed of non-corrodible metal, there being an agitator shaft 30 extending upwardly within the tub for an agitator 25 (not shown). A packing 71 is provided around the agitator shaft 30, this packing being placed in a housing 72 disposed vertically and held rigid while a spring 73 is arranged between the packing 71 to compress the same against the closed end of a gland 74 which is threaded into the housing 72, a nut 75 being disposed to coat with the upper end of the housing so that the said housing will be very firmly secured in a 30 stationary position and disassembling of the 35 parts will not be apt to occur.

While I have shown and described the reversing valve as a sliding valve, it is to be understood that the valve may be of the pivoted or rocking type and it is also to be understood that while I have shown and described that embodiment of the invention which I now prefer, various changes in the minor details of construction or arrangement of the parts may be affected without departing from the spirit or 45 scope of the invention as the same is defined in the following claim.

Having described the invention, I claim:

In a device of the kind described, the combination of an electric motor having a projecting armature shaft, a casting bolted to the motor casing and having a chamber receiving the shaft therein, a sleeve fixed to the shaft and having a helical peripheral rib, an anti-friction bearing between one end of the sleeve and the shaft end, an annular rib on the sleeve, a bellows sealed at one end to the outer end of the chamber, a spring sealing the other end of the bellows to the annular rib, said casting having a fluid way at one side of the chamber, a division wall between the fluid way and the chamber and having a port establishing communication therebetween, and a valve for controlling the outlet of fluid from the chamber. 50

RUDOLPH WITT.
